ATTORNEY

UNITED STATES PATENT OFFICE.

ALLEN P. CREQUE, OF NEWARK, NEW JERSEY.

DESIGN FOR A WASHBASIN.

SPECIFICATION forming part of Design No. 28,119, dated January 4, 1898.

Application filed November 11, 1897. Serial No. 658,211. Term of patent 14 years.

To all whom it may concern:

Be it known that I, ALLEN P. CREQUE, a citizen of the United States, residing at Newark, in the county of Essex and State of New Jersey, have invented and produced a new and original Design for a Washbasin, of which the following is a specification, reference being had to the accompanying drawings, forming part thereof.

In the drawings, Figure 1 is a plan view of my new design for a washbasin. Fig. 2 is a transverse section on line 2 2 of Fig. 1, and Fig. 3 is a section on line 3 3 of Fig. 2.

In plan view my design presents a heart-shaped configuration with the reentering lines *a* at the back of the basin and the point *b* at the front. At the innermost part *c* of the reentering portion the shell is vertical or nearly

so. Each way therefrom and up to the line *e* the shell expands in the concave part *d*, the 20 concavity being gradually increased from the back to the front. Above said line *e* the part *f* of the shell is expanded in larger measure, and also in concave form, this part being higher at the back and sloping to the front 25 and formed with a bead on the edge.

I claim—

The design for a washbasin herein shown and described.

Signed at New York, in the county of New 30 York and State of New York, this 30th day of October, A. D. 1897.

ALLEN P. CREQUE.
